UNITED STATES PATENT OFFICE.

EDWARD J. KORMAN AND MANSFIELD H. WALKER, OF CHICAGO, ILLINOIS.

DESIGN FOR A WASHTUB-SUPPORT.

No. 39,892.

Specification for Design.

Patented March 23, 1909.

Application filed December 11, 1908. Serial No. 467,107. Term of patent 7 years.

To all whom it may concern:

Be it known that we, EDWARD J. KORMAN and MANSFIELD H. WALKER, citizens of the United States, residing at Chicago, in the county of Cook and State of Illinois, have invented a new, original, and ornamental Design for Washtub-Supports, of which the following is a specification, reference being had to the accompanying drawing, forming part thereof.

The figure is a perspective view of the support.

We claim:

The ornamental design for a wash-tub support, as shown.

EDWARD J. KORMAN.
MANSFIELD H. WALKER.
